United States Patent Office

Des. 224,095
Patented July 4, 1972

224,095

COMPONENT FOR GRILL WORKS, RAILINGS, COLUMNS AND THE LIKE

Ellis Deloy Larson, 225 E. State Road,
Pleasant Grove, Utah 84062

Filed Mar. 1, 1971, Ser. No. 120,000

Term of patent 14 years

Int. Cl. D25—02

U.S. Cl. D13—1

FIG. 1

FIG. 2

FIG. 3

FIG. 4

FIG. 1 is a perspective view, illustrating my component design;

FIG. 2 is a front elevation thereof, the rear elevation of such component being identical;

FIG. 3 is a left side elevation thereof, the right side elevation of the same being identical; and

FIG. 4 is a top plan thereof, the bottom plan of such component being identical.

I claim:

The ornamental design for a component for grill works, railings, columns and the like, substantially as shown and described.
